UNITED STATES PATENT OFFICE

156,907

SEED PLANTER

Paul E. Milton, San Lucas, Calif.

Application March 1, 1948, Serial No. 144,855

Term of patent 14 years

(Cl. D35—2)

To all whom it may concern:

Be it known that I, Paul E. Milton, a citizen of the United States of America, residing at San Lucas, in the county of Monterey and State of California, have invented a new, original, and ornamental Design for a Seed Planter, of which the following is a specification, reference being had to the accompanying drawing, forming part thereof.

In the drawing:

Fig. 1 is a side elevation of a seed planter, showing the new design;

Fig. 2 is a top plan view thereof; and

Fig. 3 is a perspective view thereof.

I claim:

The ornamental design for a seed planter, as shown.

PAUL E. MILTON.
